ATTORNEY.

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed October 5, 1920. Serial No. 414,731.

To all whom it may concern:

Be it known that I, ALFRED G. F. KUROWSKI, a citizen of the United States, residing in Brooklyn Borough, in the county of Kings, city and State of New York, have invented certain new and useful Improvements in Typewriting Machines, of which the following is a specification.

This invention relates mainly to the class of portable typewriting machines, and is illustrated in connection with the Underwood standard portable typewriter. Such machines are provided with case-shift mechanisms allowing a normal and two shifted positions, as fully described in the patent to William A. Dobson, No. 1,335,956, granted April 6, 1920. In this patent, the case is supported in each of its three positions upon a support at each end, thus making a two-point support.

One feature of the present invention is the provision of a four-point support for each position of the case, to hold the carriage more rigidly, and assist to a great extent in the proper alignment of the type.

It is also aimed to accomplish the above result with a minimum of change in structure as disclosed in the Dobson patent referred to above, and by simple and inexpensive mechanism. In the Dobson patent, the case-shift frame normally rests upon a support in the base of a bracket fixed to the machine, one at each end thereof. The present invention provides for an additional support upon a bracket at each end near the rear of the shiftable case. The Dobson patent provides a stop on a bail for limiting the movement of the case-shift mechanism when the first shift-key (usually the "capital" key) is depressed. This invention contemplates the use of an additional bail upon which is mounted an additional support, the bails being connected by a link to move in unison. For the second shift position Dobson provides a stop on the upper end of the bracket mentioned above as supporting the mechanism in its normal position. An additional extension is mounted upon the same bracket in the present invention and provides a second support for the case in its second shifted position. Two supports are thus provided at each end of the machine for each position of the case-shift mechanism, i. e., a four-point sup-

port is provided for each position. It 55 should be understood that the various stops or points of support are so positioned as to insure a firm holding of the shift-frame in each of its three positions.

Other features and advantages will hereinafter appear.

In the accompanying drawings,

Figure 1 is a section of the machine on the line 1—1 of Figure 4, substantially all parts of the machine except the case-shift 65 mechanism having been removed. The case is in its normal position, the shifted positions of the platen being indicated in dotted lines.

Figure 2 is a view similar to Figure 1, 70 showing the parts in the first shift position, certain parts shown in Figure 1 having been removed.

Figure 3 is a view similar to Figure 2, 75 showing the parts in the second shift position.

Figure 4 is a plan view of the machine with most of the parts removed, leaving substantially the case-shift mechanism.

The frame of the machine is shown at 80 10, and has mounted therein character-keys (not shown) which operate type-bars 11 carrying type-blocks 12 provided with three sets of types for printing in the three positions of the platen, as indicated in Figure 85 1. The platen 13 is journaled in the carriage 14 carrying wheels 15 and 16 for movement on tracks 17 and 18 respectively. The tracks 17 and 18 are located at the rear of and form part of the shift-frame 90 19, which includes downwardly-extending member 20 and forwardly-extending member 21. This frame is pivoted at 22 to a link 23 which is in turn pivoted to the fixed frame of the machine at 24 on a level somewhat below the pivot 22 but almost directly to the rear thereof. The shift-frame is pivoted also upon a pivot-pin 26 fixed to an arm 27 rigidly mounted upon rock-shaft 30 extending transversely of the machine 100 30 and journaled in the frame thereof. Also rigidly mounted upon the shaft 30 is a rock-arm 31 terminating in a flange or elbow 32.

For supporting the case-shift mechanism in the normal position, there is provided a bracket 35 having a floor portion 36 fixed by screws 38 to a cross-piece 37 fixed in the frame of the machine. Near the end of the

2 floor portion there is provided a set-screw 40 having a locking nut 41 upon which rests a flange 42 of the shift-frame 19. In addition, there is provided a bracket 45 at the 5 rear of the machine, a set-screw 46 passing therethrough and having a locking nut 47. The rear of the frame rests upon the set-screw 46. There are thus two points of support at the end of the machine being 10 described, two similar supports being provided at the other end, making a four-point support for the normal position of the shift-frame. It will be evident that, as the result of the manner of controlling the shift-frame 19 by the links 23 and arms 27 and of the positioning of the carriage 14 on the 15 rear of the shift-frame 19, the downward pressure of the shift-frame will be exerted at the rear of the machine. Obviously, set-screws 46 at the rear of the machine are 20 well located for supporting the shift-frame, and it should be understood that the set-screws 40 are located far enough toward the front of the machine, so that the principal downward pressure of the shift-frame 19 will be directed between the front and rear set-screws or supports 40 and 46, respectively, thereby insuring the firm positioning of the platen 13 when the shift-frame 19 is in its lower-case position.

For lifting the shift-frame to its first shifted position, which, in the type of machine described, is the position for printing capitals, there is provided a shift-key 35 50 fulcrumed on a shaft mounted in a bracket 52 fixed on a transverse bar 54 attached to the machine, said shaft comprising a screw having at one end a head 53 and a nut 51 at the other end. A rearward extension 55 of the shift-key 50 lodges beneath the elbow 32 of the rock-arm 31.

Figure 2 shows the case shifted to its 45 first shift position. The shift-key 50 has been depressed, thus elevating extension 55 of the key-lever, and forcing the rock-arm 31 upward. Arm 27, and hence pivot-pin 26, will also be rocked upwardly, thus elevating frame 19 which rests upon pivot 26. Frame 19 will continue to rise until flanges 50 60 and 61 on the frame strike the set-screws 62 and 63, respectively. The set-screws are provided with locking nuts 64 and 65, and are mounted in the flanged ends 66 and 67 of the uprights 68 and 69, respectively, 55 which uprights are the upturned ends of bails 70 and 71 extending transversely of the machine and pivoted in the frame of the machine at 72 and 73, respectively.

When the shift-frame 19 is lifted from its 60 normal position to its first shift position, as shown in Figure 2, it tends to turn or rock about the pivot-pins 26. As shown in Figure 2, however, the bails 70 and 71, respectively, are positioned at the rear and front 65 of the pivot-pins 26, so that, when the

flanges 61 and 60 on said frame are brought into engagement with the respective set-screws or stops 63 and 62 on the bails, the shift-frame 19 will be held firmly in position.

Figure 3 shows the case in the second shift position in which the platen is in the highest position indicated by dotted lines in Figure 1. Shift-key 80 is depressed, and, in the type of machine described, the figures are brought into printing position. Shift-key 80 is mounted upon the same fulcrum as shift-key 50 and has a similar rearwardly extending portion 81 engaging the under side of the elbow 32 of the rock-arm 31. The latter arm moves upward, rotating arm 27, pivot 26, and shift-frame 19 upwardly, as in the first shift position. Since it is necessary to raise the shift-frame a greater degree than in the first shift position, the stops 62 and 63 must be removed from the path of motion of flanges 60 and 61 on the frame 19. This is accomplished by attaching a bracket 83 to bail 71, the bracket having an upper curved portion 84 resting on lug 85 on the rearward extension 81 of shift-key 80. A spring 86 tends to maintain the bail 71, and hence stops 62 and 63, in effective position. Upon depressing the shift-key 80, extension 81, and hence lug 85, are swung upward, the curved portion 84 (and hence the bracket itself) being swung in a clockwise direction. Since the bracket 83 is rigidly attached to bail 71, the latter is also rotated, thus swinging stop 62 out of the path of motion of flange 61. Bail 71 is connected by a link 82 with bail 70, so that both bails, and hence both set-screws or stops, are moved out of the path of motion of the flanges 60 and 61. Other stops are provided to limit the motion of the case-shift mechanism when key 80 is depressed. These stops consist of two arms 87 and 88 of the bracket 35 which also supports stop 40. In the flanged ends 89 and 90 of the arms 87 and 88 are mounted set-screws 91 and 92 having the usual lock-nuts 93 and 94, and serving to fix the second shift position of the mechanism when key 80 is depressed by engaging the flange 42 on the shift-frame.

As a result of the control of the shift-frame 19 by the long links 23 and the arms 27, the shift-frame 19 will, in its movement to its second shift position, be given a movement in which it is thrown upward to a greater extent at the rear than at the front, and it should be understood that the set-screws or stops 91 and 92 are suitably positioned to check this tendency and to hold the shift-frame firmly against rocking while in its third shift position.

It is usual to provide springs (not shown in this instance) to draw keys 50 and 80 upward. The rearward extensions of the keys

are provided with depending fingers 97 and 98 (Figure 2) which abut against the fixed bar 54 to limit such upward movement.

It will be understood that with the exception of the keys 50 and 80 and their extensions 55 and 81 and the rock-arm 31, all the mechanism is duplicated at the other end of the machine, so that in the normal position of the machine there are stops 40 and 46 at each end of the machine, making a four-point support. Similarly in the first shifted position, there are stops 62 and 63 at both ends of each bail, one on either side of the machine, making four points of contact with the case-shift mechanism in the first shifted position. Set-screws 91 and 92 form two stops at each end of the machine, thus also giving four points of contact with the case-shift mechanism in the second shifted position.

Variations may be resorted to within the scope of the invention, and portions of the improvements may be used without others.

Having thus described my invention, I claim:

1. In a typewriting machine, in combination a platen, a traveling platen-carriage, a shift-frame on which said platen-carriage is supported, a stationary stop at each side of the machine to support the rear of said shift-frame, and a second stationary stop at each side of the machine to engage and support the adjacent side of the shift-frame and spaced to the front from the corresponding stop for the rear of the shift-frame, the construction and arrangement being such that the downward pressure of the shift-frame will be directed between the front and rear stops, thereby insuring a firm, stable support for the platen and shift-frame in lower-case position.

2. In a typewriting machine, in combination, a platen, a traveling platen-carriage, a shift-frame on which the platen-carriage is supported, a stationary stop at each side of the machine to support the rear of the shift-frame, a second stationary stop at each side of the machine to engage and support the adjacent side of the shift-frame and spaced to the front from the corresponding stop for the rear of the shift-frame, the construction and arrangement being such that the downward pressure of the shift-frame will be directed between the front and rear stops, whereby a firm, stable support for the platen and shift-frame in lower-case position is provided, and means for individually adjusting said front and rear stops to locate them to be engaged simultaneously by the shift-frame when the latter drops to lower-case position.

3. In a typewriting machine, in combination, a platen, a platen-carriage, a shift-frame on which said platen-carriage is supported, said shift-frame including side

frames, shift-frame-lifting means pivotally connected with the side frames of the shift-frame at points in alignment transversely of the machine, and two stops to engage each side frame to limit the upward movement of the shift-frame and positioned to engage the side frame at points to the front and rear of the corresponding pivotal connection, so as to hold the shift-frame firmly in position when shifted. 70 75

4. In a typewriting machine, in combination, a platen, a platen-carriage, a shift-frame on which said platen-carriage is supported, said shift-frame including side frames, means for shifting said shift-frame to two different positions, comprising two aligned pivots engaging the side frames of the shift-frame, two stops to engage each side frame to limit the movement of the shift-frame and positioned to engage the 80 85 side frame at points to the front and rear of the corresponding pivot, so as to hold the shift-frame firmly in one of said positions when shifted, and means whereby said stops may be shifted out of the path of the side frames of the shift-frame, thereby permitting the shift-frame to be given a further movement to the other of said positions. 90

5. In a typewriting machine, in combination, a platen, a platen-carriage, a shift-frame on which said platen-carriage is supported, said shift-frame including side frames, means for lifting said shift-frame to two different positions, comprising two aligned pivot-pins engaging the side 100 105 frames of the shift-frame, two stops to engage each side frame to limit the upward movement of the shift-frame and positioned to engage the side frame at points to the front and rear of the corresponding pin, so as to hold the shift-frame firmly in position when shifted to the first raised position, means whereby said stops may be shifted out of the path of the side frames of the shift-frame, thereby permitting the shift-frame to be given a further movement to a second raised position for typing in another case, and two stops for each of the side frames of the shift-frame to determine accurately the uppermost position of the shift-frame and to assist in holding the latter firmly in such position. 110 115

6. In a typewriting machine, in combination, a platen, case-shift mechanism for shifting said platen from its normal position to different shift positions, said case-shift mechanism comprising a shift-frame having side frames, and shifting means having pivotal connections with each of the side frames, an upright pivoted bail at the front of the pivotal connections, and having means for engaging said side frames when the shift-frame is moved to the corresponding shift position, and a second upright pivoted bail to the rear of said pivotal connections, and 120 125 130

- having means to engage said side frames and to co-operate with the frame-engaging means on the first-mentioned bail, to hold the side frames against further movement.

7. In a typewriting machine, the combination with a case-shift mechanism having a normal and two shifted positions, and comprising a shift-frame having a shift-plate at each end, each of said shift-plates being provided with a plurality of flanges, of a shift-key for actuating said mechanism to the first shifted position, a second shift-key for actuating said mechanism to the second shifted position, means connecting said mechanism and said shift-keys whereby operation of said keys actuates said mechanism to the shifted positions, a plurality of bails having flanged upstanding end portions at each end of the machine, means passing through said end portions and engaging certain of the flanges on the shift-plates to limit the movement of the case-shift mechanism when the first shift-key is operated, a link connecting the bails so that all the bails will operate in unison, brackets fixed to the machine and provided with upstanding members having flanged ends, means passing through said ends and engaging certain other of the flanges on the shift-plates to limit the movement of the case-shift mechanism when the second shift-key is operated, a flange on said second shift-key, and a lever fixed at one end to one bail and having its other end resting on said last-named flange, so that operation of the second shift-key rotates the lever on the bail to move all the interlinked bails and their limiting means out of the path of the flanges on the shift-plates.

8. In a typewriting machine, in combination, a platen, case-shift mechanism for shifting said platen from its normal position to different shift positions, said case-shift mechanism comprising a shift-frame having side frames, and shifting means having pivotal connections with each of the side frames, an upright pivoted bail at the front of the pivotal connections, and having means for engaging said side frames when the shift-frame is moved to the corresponding shift position, a second upright pivoted bail to the rear of said pivotal connections, and having means to engage said side frames and to co-operate with the engaging means on the first-mentioned bail to hold the side frames against further movement, and a link connecting said bails to cause them to move simultaneously.

9. In a typewriting machine, the combination with a case-shift mechanism having a normal and two shifted positions and comprising a shift-frame having a shift-plate at each end, said shift-plates being provided with a plurality of flanges, of shift-keys for shifting said mechanism to first and second shifted positions, brackets fixed to said machine at each end near the rear thereof and having flanged end portions, second brackets fixed to the machine at each end and forwardly of said first brackets and having flanged end portions, means passing through the end portions of said first and second brackets for supporting the mechanism in its normal position, a plurality of bails pivoted to the machine and provided with upstanding portions having flanged ends, means passing through said ends and adapted to engage certain of the flanges on the shift-plates for limiting the movement of the mechanism in its first shifted position when the first shift-key is operated, upstanding members on said second brackets having flanged ends, and means passing through said last-named ends and adapted to engage certain other flanges on the shift-plates, to limit the movement of the mechanism when the second shift-key is operated.

10. In a typewriting machine, the combination with a case-shift mechanism having a normal and two shifted positions and comprising a shift-frame having a shift-plate at each end, said shift-plates being provided with a plurality of flanges, of shift-keys for shifting said mechanism to first and second shifted positions, brackets fixed to said machine at each end near the rear thereof and having flanged end portions, second brackets fixed to the machine at each end and forwardly of said first brackets and having flanged end portions, means passing through the end portions of said first and second brackets for supporting the mechanism in its normal position, a plurality of bails pivoted to the machine and provided with upstanding portions having flanged ends, means passing through said ends and adapted to engage certain of the flanges on the shift-plates for limiting the movement of the mechanism in its first shifted position when the first shift-key is operated, upstanding members on said second brackets having flanged ends, and means passing through said last-named ends and adapted to engage certain other flanges on the shift-plates, to limit the movement of the mechanism when the second shift-key is operated.

11. In a typewriting machine, the combination with a case-shift mechanism having a normal and two shifted positions and comprising a shift-frame having a shift-plate at each end, said shift-plates being provided with a plurality of flanges, of shift-keys for shifting said mechanism to first and second shifted positions, brackets fixed to said machine at each end near the rear thereof and having flanged end portions, second brackets fixed to the machine at each end and forwardly of said first brackets and having flanged end portions, means passing through the end portions of said first and second brackets for supporting the mechanism in its normal position, a plurality of bails pivoted to the machine and provided with upstanding portions having flanged ends, means passing through said ends and adapted to engage certain of the flanges on the shift-plates for limiting the movement of the mechanism in its first shifted position when the first shift-key is operated, upstanding members on said second brackets having flanged ends, and means passing through said last-named ends and adapted to engage certain other flanges on the shift-plates, to limit the movement of the mechanism when the second shift-key is operated.

- rear thereof and having flanged end portions, second brackets fixed to the machine at each end and forwardly of said first brackets and having flanged end portions, 5 means passing through the end portions of said first and second brackets for supporting the mechanism in its normal position, a plurality of bails pivoted to the machine and provided with upstanding portions having flanged ends, means passing through 10 said ends and adapted to engage certain of the flanges on the shift-plates for limiting the movement of the mechanism in its first shifted position when the first shift-key is 15 operated, a link connecting the bails so that all the bails will operate in unison, upstanding members on said second brackets having flanged ends, means passing through 20 said last-named ends and adapted to engage certain other flanges on the shift-plate to limit the movement of the mechanism when the second shift-key is operated, a spring normally holding the bails in position so that the limiting means will engage 25 the flanges of the shift-plates upon movement of the case-shift mechanism, a flange on said second shift-key, a lever fixed at one end to one bail and having its other end resting on said last-named flange, so 30 that operation of the second shift-key rotates the lever on the bail to move said interlinked bails and their limiting means out of the path of the flanges on the shift-plates.
- 35 12. In a typewriting machine, in combination, a platen, case-shift mechanism for shifting said platen from its normal position to different shift positions, said case-shift mechanism comprising a shift-frame 40 having side frames, and shifting means having pivotal connections with each of the side frames, an upright pivoted bail at the front of the pivotal connections, and having means for engaging said side frames 45 when the shift-frame is moved to the corresponding shift position, a second upright pivoted bail to the rear of said pivotal connections, and having means to engage said side frames and to co-operate with the engaging means on the first-mentioned bail to hold the side frames against further movement, and means to shift said bails to ineffective position, said last-mentioned means comprising a shift-lever for effecting a 55 movement of the shift-frame further than the position determined by said bails, a link connecting said bails, and an arm on one of said bails to be engaged and actuated by said shift-lever.
- 60 13. In a typewriting machine, in combination, a platen, case-shift mechanism for shifting said platen from its normal position to different shift positions, said case-shift mechanism comprising a shift-frame having side frames, and shifting means having pivotal connections with each of the side frames, an upright pivoted bail at the front of the pivotal connections, and having a stop to engage each side frame when the shift-frame is moved to the corresponding shift position, a second upright pivoted bail to the rear of said pivotal connections, and having a stop to engage each side frame and to co-operate with the stop on the first-mentioned bail to hold the side frames against further movement, a shift-key to actuate said shifting means to shift said shift-frame to a shift position corresponding to the position of the stops on said bails, a second shift-key to actuate said shifting 70 means to shift the shift-frame to a shift position beyond that determined by the stops on said bails, and means whereby actuation of the second shift-key will cause both of said bails to be shifted to ineffective position.
- 75 14. In a typewriting machine, in combination, a platen, case-shift mechanism for shifting said platen from its normal position to different shift positions, said case-shift mechanism comprising a shift-frame having side frames, and shifting means having pivotal connections with each of the side frames, an upright pivoted bail at the front of the pivotal connections, and having a stop to engage each side frame when the shift-frame is moved to the corresponding shift position, a second upright pivoted bail to the rear of said pivotal connections, and having a stop to engage each side frame and to co-operate with the stop on the first-mentioned bail to hold the side frames against further movement, a shift-key to actuate said shifting means to shift said shift-frame to a shift position corresponding to the position of the stops on said bails, a second shift-key to actuate said shifting 80 means to shift the shift-frame to a shift position beyond that determined by the stops on said bails, and means whereby actuation of the second shift-key will cause both of said bails to be shifted to ineffective position.
- 85 15. In a typewriting machine, in combination, a platen, case-shift mechanism for shifting said platen from its normal position to different shift positions, said case-shift mechanism comprising a shift-frame having side frames, and shifting means having pivotal connections with each of the side frames, an upright pivoted bail at the front of the pivotal connections, and having a stop to engage each side frame when the shift-frame is moved to the corresponding shift position, a second upright pivoted bail to the rear of said pivotal connections, and having a stop to engage each side frame and to co-operate with the stop on the first-mentioned bail to hold the side frames against further movement, a shift-key to actuate said shifting means to shift said shift-frame to a shift position corresponding to the position of the stops on said bails, a second shift-key to actuate said shifting 90 means to shift the shift-frame to a shift position beyond that determined by the stops on said bails, and means whereby actuation of the second shift-key will cause both of said bails to be shifted to ineffective position.
- 95 16. In a typewriting machine, in combination, a platen, case-shift mechanism for shifting said platen from its normal position to different shift positions, said case-shift mechanism comprising a shift-frame having side frames, and shifting means having pivotal connections with each of the side frames, an upright pivoted bail at the front of the pivotal connections, and having a stop to engage each side frame when the shift-frame is moved to the corresponding shift position, a second upright pivoted bail to the rear of said pivotal connections, and having a stop to engage each side frame and to co-operate with the stop on the first-mentioned bail to hold the side frames against further movement, a shift-key to actuate said shifting means to shift said shift-frame to a shift position corresponding to the position of the stops on said bails, a second shift-key to actuate said shifting 100 means to shift the shift-frame to a shift position beyond that determined by the stops on said bails, and means whereby actuation of the second shift-key will cause both of said bails to be shifted to ineffective position.
- 105 17. In a typewriting machine, in combination, a platen, case-shift mechanism for shifting said platen from its normal position to different shift positions, said case-shift mechanism comprising a shift-frame having side frames, and shifting means having pivotal connections with each of the side frames, an upright pivoted bail at the front of the pivotal connections, and having a stop to engage each side frame when the shift-frame is moved to the corresponding shift position, a second upright pivoted bail to the rear of said pivotal connections, and having a stop to engage each side frame and to co-operate with the stop on the first-mentioned bail to hold the side frames against further movement, a shift-key to actuate said shifting means to shift said shift-frame to a shift position corresponding to the position of the stops on said bails, a second shift-key to actuate said shifting 110 means to shift the shift-frame to a shift position beyond that determined by the stops on said bails, and means whereby actuation of the second shift-key will cause both of said bails to be shifted to ineffective position.
